UNITED STATES PATENT OFFICE.

ARTHUR J. MORSE, OF SALISBURY, CONNECTICUT, ASSIGNOR TO THE MORSE-KEEFER CYCLE SUPPLY COMPANY, OF SAME PLACE.

SLOTTING AND SLABBING MACHINE.

SPECIFICATION forming part of Letters Patent No. 628,410, dated July 4, 1899.

Application filed August 10, 1897. Serial No. 647,746. (No model.)

To all whom it may concern:

Be it known that I, ARTHUR J. MORSE, of Salisbury, in the county of Litchfield, in the State of Connecticut, have invented new and useful Improvements in Slotting and Slabbing Machines, of which the following, taken in connection with the accompanying drawings, is a full, clear, and exact description.

My invention relates to slotting and slabbing machines for use in manufacturing nipples for bicycle-spokes or other similar devices; and the object is to provide a machine that will operate on several nipples or other articles at once, producing a somewhat different operation on each, and that will operate upon said nipples successively.

To this end my invention consists in the combination, in a nipple-slabbing machine, of a disk provided with chambers to hold the nipples, means to rotate the disk intermittently, a sliding bar carrying a rotatable spindle on one end extending parallel with a face of the disk, two sets of cutters on the spindle to operate simultaneously on a pair of nipples, and suitable means to reciprocate the sliding bar; and my invention consists in certain other combinations of parts hereinafter described, and specifically set forth in the claims.

In the drawings hereto annexed and forming a part of this specification, Figure 1 is the top plan view of my invention. Fig. 2 is the front side elevation. Fig. 3 is the rear side elevation. Fig. 4 is an end elevation looking from right to left of Fig. 1. Fig. 5 is an end view of some of the important movable parts in the opposite position from that indicated in Fig. 4. Fig. 6 is an end view of the machine, looking from left to right of Figs. 1 and 2. Fig. 7 is a side elevation of the spindle or spindles carrying the slabbing-cutters. Fig. 8 is a section of the presser-plate which holds the nipples in the disk, and Fig. 9 shows a nipple before and after it is slabbed.

Referring specifically to the drawings, A is the frame of the machine, having forward extensions *a* and *a'* for the sliding bar B to move on and rearward extensions *b* *b'* for the sliding bar C to move on. Another pair of extensions *c* *c'* and *c''* are above the extensions

b and *b'* to provide bearings for the driving-shaft D, which carries a cam-wheel D' to move the sliding bar C below it, and a cog-wheel E, which meshes with a cog-wheel E' on a short shaft F, turning in bearings over the center 55 of the frame A. The shafts D and F are parallel with each other and lie with their axes in the same horizontal plane. The shaft F also carries a cam-wheel F', which engages a roller B' on the inside of the sliding bar B to 60 move the bar toward the disk G, which carries the nipples to be and in the process of being slabbed and slotted.

The disk G is secured on one end of a horizontal shaft G', which turns in bearings *g* *g'* 65 in a bracket G'', secured to the front side of the frame A.

D'' is the driving-wheel on the shaft D.

The cam-wheel F' is designed to move the bar B longitudinally toward the disk G once 70 during each revolution, and a coil-spring *d*, connected between the said bar and the extension, serves to retract the bar or draw it away from the disk. The disk G is provided with a circular series of holes which extend through it near its periphery to hold the nipples. Twenty holes are shown in the disk in the drawings, and these holes are just large enough to admit the shanks of the nipples, which have the appearance of rivets, and are 80 countersunk slightly to partly receive the heads. In order to hold the nipples in and to prevent them from turning while they are being operated upon, I provide a bracket H, having a curved arm secured by screws to a 85 segment of a disk *h*, which carries a curved tension-plate *h'* on the side next the disk in the path of the heads of the nipples. The tension-plate *h'* is curved outward at the receiving end to allow the heads to pass easily 90 between it and the disk. The construction of this segment *h* is shown clearly in Fig. 8 of the drawings. This view shows the plate *h'* held in a groove in the segment *h* by a pair of curved strips *h''* *h'''*, screwed to the segment. A curved plate *i* is in the bottom of the groove to form a bearing for the ends of a series of adjusting-screws *i'* *i''*, &c., which pass through the segment to increase the tension, and a soft-rubber strip is placed between 95 100

the plate *h'* and the plate *i*. The bracket *H* extends horizontally and lies against the rear side of the frame *A* and is adjustable toward and from the disk *G* by means of screws *j j*, passing through short slots in the bracket.

The nipples are inserted by hand in the disk, which revolves in the direction of the arrow. (Shown in Fig. 6.) When a nipple reaches a point forty-five degrees above a horizontal plane extending through the axis of the shaft *G'*, it is slabbed or made flat on a portion of two opposite sides, after which it is carried by the disk a distance of ninety degrees, during which it is turned over one-fourth, allowing cutters mounted on the same spindle as the other cutters to slab or flatten the other two sides, thus forming a square section on the shank of the nipple for the application of a wrench when it is turned on a spoke. After the same nipple is carried by the disk about fifty degrees, more or less, farther it is then in position to have its head slotted or recessed for receiving a screw-driver, as usual, and when it has been carried a few degrees farther it is pushed out of the disk by a pusher *L* automatically with the other operations.

A brief description of the operations has been given before the parts have been fully specifically described to prepare for a clear understanding of the operation of said parts, which will be hereinafter fully described.

The end of the sliding bar *B* nearest the disk is made broad and is provided with a pair of bearings *k k* for the spindle *I'* of the slabbing-cutters *I I*, which are arranged in pairs for the purpose of slabbing two sides at once. The cutters are of the usual form—namely, disks with serrated peripheries—and they are suitably mounted to turn with the spindle, and they are separated to allow the ends of the nipples to pass between them.

I' is a pulley in the center of the spindle and between the bearings *k k* for the belt which drives the spindle. The cutters *I I* rotate continuously, and when the disk is stationary the cutters are made to approach the disk and slab two sides of a pair of nipples. Then the bar *B*, carrying the cutters, is retracted by the spring *d*, after which the disk is revolved the distance between two nipples, which brings two other nipples in position to be slabbed, when the bar and cutters are forced toward the disk as before. The spindle for the cutters is divided in the center, so that one or the other end may be removed without removing the other. The inner ends of the spindle are lapped over each other with a flat bar *l* between, which bar extends diametrically through the pulley, as shown in Fig. 7 of the drawings. I do not limit myself to this form of connection, however, as it may be made in various ways. The spindles are held in place and in their bearings by angular arms *m m*, secured to the bar and extending outward opposite the ends of the spindles, and adjusting-screws *m' m'*, passing

through the ends of the arms and bearing with their ends on the ends of the spindle *I'*, as shown clearly in Fig. 1 of the drawings.

The shaft *G'* is rotated intermittently by means of a ratchet-wheel *J* on the end opposite that carrying the disk *G*. The ratchet-wheel is provided with as many teeth as there are holes for nipples in the disk, the number in this case being twenty. The recesses in the periphery of the ratchet-wheel are shown square and are preferably made square in order that the disk may be held positively against movement in either direction during the slabbing and slotting operations.

J' is the pawl for turning the ratchet-wheel. Said pawl is connected at one end with an upwardly-extending arm of a bell-crank lever *K*, pivoted to the frame. The pawl *J'* is adjustable universally in a vertical plane by slots and screws. (Not necessary to be specified.) The other arm of the bell-crank lever is connected by a coil-spring *n* with the base of the machine to carry the pawl longitudinally when released.

The pawl *J'* is operated to turn the ratchet-wheel by means of a roller *k'*, carried on a short arm or projection *k''*, extending from a sleeve *k'''* on the driving-shaft, striking during each revolution of the shaft the upwardly-extending arm of the lever *K*. A stop-screw *o* is shown extending through the frame to engage the horizontal arm of the lever *K* and prevent the spring *n* from retracting the lever too far. Another cam *p* on the sleeve operates a pawl or detent *p'*, pivoted intermediate its length, which holds the ratchet-wheel against movement during each operation by means of a square lug on its free end entering the square recesses in the ratchet-wheel *J*. The pawl *p'* is seated by a spring *p''*.

M is the spindle, carrying the single cutter *N* on one end for slotting the heads of the nipples after they have been slabbed. This spindle turns in bearings *q q* on the broad end of the sliding bar *C* before referred to. The cutter *N* is on the opposite side of the disk from the slabbing-cutters.

Q is the pulley on the spindle *M* for driving the spindle. The head of a nipple is slotted while two other nipples are being slabbed and, of course, while the disk is stationary. Therefore the sliding bars *B* and *C* are moved by their cams simultaneously in opposite directions, the disk only turning when the said bars are receding from it. A bifurcated spring-plate *N'* is secured on the end of the bracket *H* to bear upon the head of the nipple while it is being slotted by the cutter *N* to hold it stationary, as clearly shown in Figs. 3 and 6 of the drawings.

The pusher *L* (shown in Fig. 2 of the drawings) consists of a short rod, which works longitudinally through a stud *r*, mounted in the frame. One end of the rod is connected with one side of the bar *B* by a depending bar *r'*, and the pusher is reciprocated by and with said bar *B*. The other end of the pusher is

adapted to strike the end of a nipple and push it out of its aperture in the disk.

I do not wish to be limited to the precise construction of parts shown, as it will be obvious that they may be changed widely without departing from my invention.

Having described my invention, what I claim as new, and desire to secure by Letters Patent, is—

- 10 1. In a slotting and slabbing machine for nipples, the combination of a disk provided with chambers to hold the nipples, means to rotate the disk intermittently, a longitudinally-reciprocating bar carrying a rotatable spindle extending parallel with a face of the disk, two pairs of cutters on the spindle to slab simultaneously a pair of nipples, suitable means to operate the bar, a second reciprocating bar carrying a spindle on the opposite side of the disk, a cutter on the latter spindle to slot the heads of the nipples, a tension-plate to retain the nipples in the disk while they are being operated upon, and means to drive the spindles, as set forth.
- 15 2. In a slotting and slabbing machine for nipples, the combination of a disk provided with chambers to hold the nipples, means to rotate the disk intermittently, a longitudinally-reciprocating bar carrying a rotatable spindle extending parallel with a face of the disk, two pairs of cutters on the spindle to slab simultaneously a pair of nipples, suitable means to operate the bar, a second reciprocating bar carrying a spindle on the opposite side of the disk, a cutter on the latter spindle to slot the heads of the nipples, a tension-plate to retain the nipples in position in the disk, while they are slabbed, means to drive the spindles, and a pusher connected with one 20 of the reciprocating bars to remove the nipples from the disk, as set forth.
- 25 3. In a slotting and slabbing machine for nipples, the combination of a disk provided with chambers to hold the nipples, means to rotate the disk intermittently, a longitudinally-reciprocating bar carrying a rotatable spindle extending parallel with a face of the disk, two pairs of cutters on the spindle to slab simultaneously a pair of nipples, suitable means to operate the bar, a second reciprocating bar carrying a spindle on the opposite side of the disk, a cutter on the latter spindle to slot the heads of the nipples, a curved tension-plate to retain the nipples in position in the disk while they are slabbed, means to drive the spindles, and a pusher to remove the nipples from the disk consisting of a longitudinally-movable rod in a guideway, said rod being parallel with the shaft of the disk and 30 movable in the path of the nipples, and a connecting-bar between the said rod and one of the said reciprocating bars, as set forth.
- 35 4. In a slabbing-machine for nipples, the combination with the frame, of a disk provided with a circular series of apertures to hold the nipples, a shaft for the disk carrying a ratchet-wheel, a driving-shaft, a shaft car-

rying a cam-wheel parallel with the driving-shaft and geared to the latter, a cam on the driving-shaft, a pawl to rotate the ratchet-wheel operated by the cam on the driving-shaft, a longitudinally-movable bar operated by the said cam-wheel, a spindle carried by the bar, a pair of cutters on the spindle, and a pulley on the spindle, substantially as described and shown.

5. In a slabbing-machine for nipples, the combination with the frame, of a disk provided with a circular series of apertures to hold the nipples, a shaft for the disk carrying a ratchet-wheel, a driving-shaft, a shaft carrying a cam-wheel parallel with the driving-shaft and geared to the latter, a cam on the driving-shaft, a pawl to rotate the ratchet-wheel operated by the cam on the driving-shaft, a longitudinally-movable bar operated by the said cam-wheel, a spindle carried by the bar parallel with a face of the disk, a pair of separated cutters on each end of the spindle, and a pulley on the spindle between the bearings, substantially as described and shown.

6. In a slabbing-machine for nipples, the combination with the frame, of a disk provided with a circular series of apertures to hold the nipples, a shaft for the disk carrying a ratchet-wheel, a driving-shaft, a shaft carrying a cam-wheel parallel with the driving-shaft and geared to the latter, a cam on the driving-shaft, a pawl to rotate the ratchet-wheel, a bell-crank lever having an arm for engagement with the cam, and an arm connected with a spring, the first-mentioned arm being connected with the said pawl, a longitudinal movable bar operated by the said cam-wheel, a spindle carried by the bar, and a pair of cutters on the spindle, substantially as and for the purpose described.

7. In a slabbing-machine for nipples, the combination with the frame, of a disk provided with a circular series of apertures to hold the nipples, a shaft for the disk carrying a ratchet-wheel, a driving-shaft, a shaft carrying a cam-wheel parallel with the driving-shaft and geared to the latter, a cam on the driving-shaft, a pawl to rotate the ratchet-wheel, a bell-crank lever having an arm for engagement with the cam and an arm connected with a spring, the first-mentioned arm being connected with the said pawl, a detent for the ratchet-wheel, a cam on the driving-shaft to operate the detent, a longitudinally-movable bar operated by the said cam-wheel, a spindle carried by the bar, and a pair of cutters on the spindle, substantially as described and shown.

8. In a machine of the class described, the combination with the frame, of a disk provided with a circular series of apertures to hold the nipples, a segment of a disk supported stationarily near one face thereof, a curved groove in the segment in the path of the nipples, a pair of curved plates in the groove, one of which is adapted to bear upon the

heads of the nipples in the disk, a rubber strip between the two plates, adjusting-screws passing through the segment and bearing on one of the curved plates, means to cut the nipples while they are held in the disk, and means to intermittently rotate the disk, substantially as described and shown.

9. In a machine of the class described, the combination with the frame, of a disk provided with a circular series of apertures extending parallel with its axis to hold the nipples, means to rotate the disk intermittently, a driving-shaft, a cam-wheel on the said shaft, a horizontal longitudinally-movable bar operated by the cam-wheel, a spindle carried in bearings on one end of the bar, a cutter on the spindle to slot the heads of the nipples, and a pulley on the spindle, substantially as described and shown.
10. In a machine of the class described, the combination with the frame, of a disk provided with a circular series of apertures to hold the nipples, means to rotate the disk intermittently, a driving-shaft, a cam-wheel on

the said shaft, a longitudinally-movable bar 25 operated by the cam-wheel, a spindle carried in bearings on one end of the bar, a cutter on the spindle to slot the heads of the nipples, a bifurcated spring-plate secured to the frame and adapted to bear upon the head of the nipple while it is being slotted, as and for the purpose described.

11. The combination with the bar, B, the pair of bearings at one end, the pulley between the bearings, a bar extending through 35 the pulley diametrically, a divided spindle in the bearings having its inner ends passing on opposite sides of the bar in the pulley, cutters on the outer ends of the pulley, and angular adjustable arms carried by the bar, B, to retain the spindle in the bearings, substantially as described and shown.

In testimony whereof I have hereunto signed my name.

ARTHUR J. MORSE. [L. S.]
